DESIGN FOR A DRESS

Marie Guarino, Brooklyn, N. Y.

Application August 23, 1937, Serial No. 71,238

Term of patent 3½ years

To all whom it may concern:

Be it known that I, Marie Guarino, a citizen of the United States of America, residing in Borough of Brooklyn, city of New York, county of Kings, and State of New York, have invented a new, original, and ornamental Design for a Dress, of which the following is a specification, reference being had to the accompanying drawing, forming part thereof,

Fig. 1 is a front view of the dress showing my new design.

Fig. 2 is a rear view thereof.

I claim:

The ornamental design for a dress substantially as shown.

MARIE GUARINO.
